DESIGN FOR A LIQUID COOLER AND
CONTAINER

William L. Verch, Yonkers, N. Y.

Application February 17, 1948, Serial No. 144,541

Term of patent 7 years

(Cl. D58—8)

To all whom it may concern:

Be it known that I, William L. Verch, a citizen of the United States, residing in Yonkers, in the county of Westchester and State of New York, have invented a new, original, and ornamental Design for a Liquid Cooler and Container, of which the following is a specification, reference being had to the accompanying drawings, forming a part thereof.

Fig. 1 is a top plan view of a liquid cooler and container, showing my new design;

Fig. 2 is a side view; and

Fig. 3 is a side view with the container rotated 90° from the position shown by Fig. 2.

I claim:

The ornamental design for a liquid cooler and container, as shown.

WILLIAM L. VERCH.
